CLAIM

The ornamental design for klick desk, as shown and described.

DESCRIPTION

FIG. 1 is a perspective view of a klick desk, showing my new design in an assembled configuration;

FIG. 2 is a front elevational view of a desk portion of the invention;

FIG. 3 is a rear elevational view of the desk portion of the invention;

FIG. 4 is a left-side elevational view of the desk portion of the invention, the right- side elevational view being a mirror image thereof;

FIG. 5 is a top plan view of the desk portion of the invention;

FIG. 6 is a bottom plan view of the desk portion of the invention;

FIG. 7 is a front elevational view of a seat portion of the invention;

FIG. 8 is a rear elevational view of the seat portion of the invention;

FIG. 9 is a left-side elevational view of the seat portion of the invention, the right- side elevational view being a mirror image thereof;

FIG. 10 is a top plan view of the seat portion of the invention; and,

FIG. 11 is a bottom plan view of the seat portion of the invention.
